DISPLAY RACK

Harold F. Temple, Garden City, N. Y., assignor to
P. Lorillard Company, New York, N. Y., a corporation of New Jersey

Application December 5, 1951, Serial No. 259,920

1 Claim. (Cl. 211—85)

1 This invention relates to display racks and more particularly to racks for holding columns of articles such as cigarette cartons and the like. A popular method of merchandizing packaged products involves the displaying of the products so that the purchaser may himself select and extract a desired product from among the selection offered. In the case of self-service displays for cartons of cigarettes, the arrangement should be such that each of the several brands offered is identifiable. Further, the cartons should be so supported that a desired brand may be extracted from the display without deranging the remaining cartons.

To this end the present invention provides an improved display rack for cigarette cartons and the like which is fabricated from wire to provide a framework which is light in weight and relatively inconspicuous, but which is capable of supporting a large supply of cigarette cartons.

The rack is arranged, according to the invention, with hinged sides and shelves so that it may be folded flat to facilitate shipping, handling and storing. Front divider and shelf components are provided with simple hook means so that the sides of the unit may be held open and the shelves supported without the use of special tools or complicated fasteners. The front divider is preferably supported by the side portions in a position to afford additional support for the shelves. The basic structure is such that shelves may be provided in sufficient numbers to accommodate cartons of a large number of cigarette brands, each brand having one or more of its own shelves to avoid the necessity of stacking cartons of one brand directly on top of cartons of another brand.

The invention, as well as other features and advantages thereof may be better understood by referring to the following specification describing a preferred form of the invention and taken in conjunction with the accompanying drawing in which

Figure 1 is a view, in perspective, of a portion of a display rack unit in a stage of assembly;

Figure 2 is a front divider portion adapted to be combined with the portion of Fig. 1 to form a complete unit;

Figure 3 is a view, in perspective, of a complete and assembled unit; and

Figure 4 is a view, in perspective, corresponding to Fig. 3, but showing the unit filled with cartons for display purposes.

Referring to Figure 4, the invention is shown in the form of a wire rack 10 for supporting a plurality of cigarette cartons C, the cartons being

10 supported in double columns 11, 12, 13, 14 and 15, with their ends contained in a common vertical plane at the forward end of the rack. The respective double columns are supported by lower shelf portions 11a, 12a, 13a, 14a and 15a, and each column is divided by intermediate shelf portions 11b, 12b, 13b, 14b and 15b. If desired, one or more of the columns may be subdivided, as by a shelf portion 15c, for example.

15 The unit is comprised of a back portion 16, side portions 17 and 18, and a front or column dividing portion 19, which is mounted just rearwardly of the forward plane of the exposed ends of the cartons. The cartons C in the lower halves of the respective columns may be identified by name plates (not shown) received in name plate holders 20, and the cartons in the upper halves may be identified by means of name plates received in holders 21. If desired, a large holder 22 for a display-identifying sign may be supported at the top of the rack.

20 As best seen in Fig. 1, the back portion 16 comprises a series of horizontal or transverse members 23, which may be formed of heavy gauge wire, and the ends of which are formed with hinging loops 23a. The horizontal members 23 are attached, as by welding, soldering or the like, to a series of vertical members 24, also formed of wire. The outermost vertical members 24 may be extended upwardly to support the sign holder 22 and name plate holder 21. A diagonal member 25 may be attached to the back portion for purposes of rigidity.

25 Each of the side portions 17 and 18 is comprised of an inverted, U-shaped wire frame 26 having depending vertical limbs or members 26a. Each frame 26 is hinged to the back portion 16 by means of a vertical member 26a received in the hinging loops 23a of the back portion. Each 30 of the vertical members 26a is formed at its depending end with a foot portion 26b and a series of horizontal or transverse members 27 are attached to the vertical members. Supplementary frame portions 28 may be secured within the side portions 17 and 18 to provide reinforcement and, if desired, to provide side panels for holding additional signs. Certain of the horizontal members 27 underlie and certain overlie the hinging loops 23a of the back portion 16 so that the latter is secured against vertical movement.

35 Hingedly attached to the lower horizontal member 23 of the back portion 16 is a lower shelf assembly including the individual shelf portions 11a . . . 15a. Attached to an intermediate horizontal member 23 is the intermediate shelf assem-

bly comprising the shelf portions 11a . . . 15b. The shelf portions are comprised of a number of hinging members 29, the inner ends of which are looped about the horizontal members 23 of the back portion and the outer ends of which are attached to a pair of horizontal supporting members 30. Opposite ends of the horizontal members 30 are formed with downwardly opening hooks 30a. The individual shelf portions 11a . . . 15a and 11b . . . 15b are attached to the horizontal members 30 and comprise U-shaped elements, the closed ends of which are upturned to form vertical barriers for defining the positions of the lowermost cartons or for supporting name plate holders if such are used. The single shelf portion 15c may be hingedly attached directly to a back member 23.

The unit is completed by means of the column dividing portion 19 which comprises three horizontal or transverse members 31 formed at their respective ends with downwardly opening hooks 31a. The horizontal members are joined by a series of vertical members 32 which are spaced apart by a distance corresponding to the width of a double column. A support 32a may be provided at the bottom of the dividing portion to assist in handling and assembling.

The unit is assembled by swinging the side portions 17 and 18 forwardly so that the dividing portion 19 may rest, by means of its hooks 31a, on certain of the horizontal members 27 of the side portions. The lower and intermediate shelf portions are at the same time swung downwardly to rest on the horizontal members 31 of the dividing portion 19 and also so that the hooks 30a thereof may engage horizontal members 27 of the side portions. Wire guides 33 may be attached to the side portions to set the position of the divider at a point spaced slightly rearwardly of the forward ends of the shelf portions. The hinged, single shelf portion 15c, which subdivides the right hand column into three parts, is supported by means of a shoulder 34 attached to one of the upright members 32 of the divider portion and by a second shoulder 35 attached to the side portion 17.

The unit may be knocked down by detaching the dividing portion 19, swinging the shelf portions upwardly 90 degrees and swinging the side portions backwardly 270 degrees to engage the back surface of the back portion 16. A flat unit results which may be conveniently shipped, stored and the like. It will be understood that the unit may be quickly assembled without the use of special tools or clamping fixtures into a light-weight, rigid, quadrilateral structure having a plurality of shelf portions for supporting columns of packaged articles, such as cartons of cigarettes, for example.

The cartons are stacked as best seen in Fig. 4 in double columns which are so divided by the vertical members 32 that a large number of different brands may be accommodated and so that a carton of any particular brand may be readily extracted by a purchaser.

It will be understood that the width of certain of the shelf portions may be increased to accommodate cartons for large size cigarettes. Fur-

ther, the number of shelves provided may be widely varied to suit particular needs. The invention should not, therefore, be limited save as described by the following claim:

I claim:

A collapsible display rack comprising a pair of side portions having their respective peripheries defined by a wire bent into an inverted U configuration in which the depending ends of the vertical limbs are upturned to form foot-portions for the rack, transverse supporting members bridging the vertical limbs, a back portion comprising a plurality of vertically spaced-apart horizontal wire members, the respective ends of at least some of which are looped about the rear-most vertical limbs of the respective side portions, whereby the side portions may be swung between an inactive position in the plane of the back portion and an active position normal to the plane of the back portion, a diagonal member and a plurality of vertical members attached to the horizontal members of the back portion, a plurality of shelf portions pivotally attached to horizontal members of the back portion and adapted to be swung between horizontal and vertical planes, said shelf portions including a plurality of hinging members having their ends looped about horizontal members of the back portion, a plurality of horizontal shelf members joined to said hinging members and having downwardly opening hook portions formed on opposite ends thereof to engage the transverse supporting members of said side portions, a plurality of U-shaped shelf members attached to said horizontal shelf members and adapted to project forwardly in cantilever fashion beyond the forwardly disposed vertical limbs of the side portions, upturned end portions on said U-shaped shelf members, and a front portion for anchoring the side portions in their active positions, for affording additional support for said shelf portions and for defining product receiving columns, said front portion comprising a plurality of vertically spaced-apart horizontal wire members and a plurality of horizontally spaced-apart vertically disposed wire members, said horizontal members being formed with downwardly opening hook portions to attach to the supporting members of said side portions, whereby said horizontal wire members of the front portion underlie the shelf portions at points spaced inwardly from the upturned end portions of the U-shaped members of the shelf portions, said assembled rack being adapted to support product containers and the like stacked on said respective shelf portions in columns defined by the vertically disposed members of the front portion.
